US0D1005287S

(12) **United States Design Patent** (10) **Patent No.:** **US D1,005,287 S**
(45) **Date of Patent:** **** Nov. 21, 2023**

(54) **WIFI EXTENDER**

(71) Applicant: **Ya Li**, Xihua County (CN)

(72) Inventor: **Ya Li**, Xihua County (CN)

(**) Term: **15 Years**

(21) Appl. No.: **29/809,938**

(22) Filed: **Sep. 30, 2021**

(51) LOC (14) Cl. **14-02**

(52) U.S. Cl.

USPC **D14/358**; D14/230

(58) **Field of Classification Search**

USPC D14/230, 240, 242, 343, 358

CPC ... H04W 8/005; H04L 61/5014; H04N 5/775;
H04N 21/43637

(57) **CLAIM**

The ornamental design for a wifi extender, as shown and described.

DESCRIPTION

FIG. 1 is a perspective view of a wifi extender showing my new design;

FIG. 2 is another perspective view of the wifi extender thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict features of the wifi extender that form no part of the claimed design.

1 Claim, 8 Drawing Sheets
